DIAL CLEANER FOR AUTOMATIC TELEPHONES

Filed Oct. 24, 1927

FIG. 1.

FIG. 2.

FIG. 3.

FIG. 4.

Inventor

AUGUSTO BISSIRI.

By Hazard and Miller
Attorneys.

UNITED STATES PATENT OFFICE

AUGUSTO BISSIRI, OF LOS ANGELES, CALIFORNIA

DIAL CLEANER FOR AUTOMATIC TELEPHONES

Application filed October 24, 1927. Serial No. 228,311.

My invention relates to cleaners, and more especially to a cleaner adapted to be secured to a dial indicator and to establish brushing contact with the dial to clean the same when the indicator moves thereover.

5 One of the objects of the preferred embodiment of my invention is the provision of a cleaner adapted to be instantly secured to, or removed from, the indicator of an automatic telephone, and having a wiper extending therefrom to establish brushing contact with the dial of the telephone so as to wipe the dust from the dial as the indicator is operated.

15 Another object is the provision of a cleaner of the above described nature, which will in no manner interfere with the normal operation of the indicator or other parts of the telephone.

20 The invention possesses other objects and features of advantage, some of which, with the foregoing, will be set forth in the following description of the preferred form of my invention which is illustrated in the drawings accompanying and forming a part of the specification. It is to be understood that I do not limit myself to the showing made by the said drawings and description, as I may adopt variations of the preferred form within the scope of my invention as set forth in the claims.

Referring to the accompanying drawings,

Figure 1 is a perspective view of an automatic telephone showing the dial cleaner of my invention, mounted thereon for position in use.

Fig. 2 is a plan view of the indicating dial of the telephone of Figure 1, with my dial cleaner mounted thereupon.

40 Fig. 3 is a sectional view of the indicating dial, showing my cleaner in elevation. The plane of section is indicated by the line 3-3 of Figure 2.

Fig. 4 is an end view of my dial cleaner and 45 a portion of the indicating dial, the direction of view being indicated by the arrow 4 of Figure 2.

50 In terms of broad inclusion, my invention comprises a cleaner adapted to be secured to an indicator mounted for movement over a

dial, the cleaner being of such nature and so positioned that it extends to the dial to establish brushing contact therewith, so that it will wipe accumulated dust from the dial as the indicator is moved across its face.

55

The preferred embodiment of my invention is intended for use with a standard automatic telephone 1, having a dial 2 fixed to the base 3, and a movable indicating dial 4 mounted above the fixed dial 2. A plurality of characters are printed upon the fixed dial 2, and a plurality of apertures 6 are provided in the indicating dial 4, one above each of the characters. In order to call a number when using such a telephone, the operator inserts his finger or a pencil into the aperture above the selected character, and then rotates the indicating dial in the proper direction until encountering the stop 7 rigid with the base 3 and extending over the indicating dial 4.

65

Ordinarily, one difficulty with such telephones is the fact that in a short time, dust will accumulate upon the fixed dial 2, often times to such an extent as to be unsightly and insanitary, and even to obliterate the characters on the dial 2.

75

It is a purpose of this invention to overcome this difficulty; and I accomplish this by means of my improved dial cleaner which comprises a base 11 having a flange 12 extending upwards and backwards therefrom as best shown in Figures 3 and 4. A pair of flanges 13 and 14, extend downwards from the base 11. All of the structure so far described is of such simple nature that it may be stamped and formed from a single sheet of suitable material which should have a sufficient degree of rigidity however, so that the indicating dial 4 of the telephone may be clamped between the base 11 and upper flange 12 to hold the cleaner in position. A wiper 16 is retained between the flanges 13 and 14, and is of such proportions that it extends to the fixed dial 2 and establishes brushing contact therewith.

85

90 It is thus seen that a wiper is provided of very small proportions, instantly attachable to the indicating dial 4 or removable therefrom. It is essential that the wiper be quite

100

small, because in operation, it is necessary for the wiper to pass freely under the stop 7 so as not to interfere with the normal operation of the indicating dial.

5 When the indicating dial is turned, as previously described, the wiper 16 brushes across the surface of the fixed dial 2, wiping the dust therefrom. The wiper 16 may be of felt, the lower edges of which may be provided with 10 a plurality of serrations 17; or, it may be composed of any other well known form of brush.

From the foregoing, it is thought that the construction, use and many advantages of the herein described dial cleaner, will be 15 readily apparent without further description.

I claim:

1. A cleaner for a dial having an indicator mounted for movement across the face thereof, said cleaner comprising a base, a resilient 20 retaining flange carried by said base and formed of a continuation of one end of the base bent back upon itself whereby the cleaner may be frictionally engaged upon said indicator, and a wiper secured to said 25 base perpendicularly to the plane thereof.

2. A cleaner for a dial having an indicator mounted for movement across the face thereof, said cleaner comprising a base, a flat retaining flange extending resiliently 30 from said base and formed of a continuation of one end of the base bent back upon itself whereby the cleaner may be frictionally engaged upon said indicator, and a wiper secured to said base perpendicularly to the 35 plane thereof.

In testimony whereof I have signed my name to this specification.

AUGUSTO BISSIRI.
